UNITED STATES PATENT OFFICE.

FLORENCE McGOWAN, OF BROOKLYN, NEW YORK, ASSIGNOR TO JOSEPH A. MORRIS & CO., OF NEW YORK, N. Y., A CORPORATION OF NEW YORK.

DESIGN FOR A COMBINED DRESS AND KNITTING BAG.

51,602.

Specification for Design.

Patented Dec. 18, 1917.

Application filed October 8, 1917. Serial No. 195,444. Term of patent 7 years.

To all whom it may concern:

Be it known that I, FLORENCE McGOWAN, a citizen of the Dominion of Canada, residing in the city of New York, borough of Brooklyn, in the county of Kings and State of New York, have invented a new, original, and ornamental Design for a Combined Dress and Knitting Bag, of which the following is a specification, reference being had to the accompanying drawings, forming a part thereof.

Fig. 2 is a rear perspective view of the same.

I claim:

The ornamental design for a combined dress and knitting bag as shown.

FLORENCE McGOWAN.
